[57] **CLAIM**

The ornamental design for a portable computer or similar article, as shown and described.

DESCRIPTION

FIG. 1 is a front perspective view of a portable com-

puter or similar article showing our new design with the screen in an open position and the back panel in a closed position.

FIG. 2 is a rear perspective view of the configuration of FIG. 1.

FIG. 3 is a frontal elevational view with the screen in an open position and the back panel in an open position.

FIG. 4 is a top plan view of the configuration of FIG. 3. FIG. 5 is a side elevational view of the configuration of FIG. 3.

FIG. 6 is an opposite side elevational view of the configuration of FIG. 3.

FIG. 7 is a rear elevational view of the configuration of FIG. 3.

FIG. 8 is a front perspective view with the screen in a closed position and the back panel in a closed position.

FIG. 9 is a rear perspective view of the configuration of FIG. 8.

FIG. 10 is a front elevational view of the configuration of FIG. 8.

FIG. 11 is a top plan view of the configuration of FIG. 8.

FIG. 12 is a side elevational view of the configuration of FIG. 8.

FIG. 13 is an opposite side elevational view of the configuration of FIG. 8.

FIG. 14 is a rear elevational view of the configuration of FIG. 8.
